UNITED STATES PATENT OFFICE

LORENZO E. CROFT, OF DENVER, COLORADO, ASSIGNOR TO GARDNER-DENVER COMPANY,
OF DENVER, COLORADO, A CORPORATION OF DELAWARE

DRILL SHARPENER

Application filed December 31, 1928. Serial No. 329,563.

The present invention relates more particularly to drill sharpeners of the type in which different pressures may be brought upon the die members for forging or holding purposes, the object being to provide a more effective connecting means between the pistons and movable die member so as to prevent canting or cocking of the movable parts.

In the accompanying drawings:

10 Figure 1 is a vertical sectional view through one embodiment of the invention.

Figure 2 is a vertical sectional view on the line 2—2 of Figure 1.

15 Figures 3 and 4 are horizontal sectional views respectively on the lines 3—3 and 4—4 of Figure 2.

20 Figure 5 is a detail vertical sectional view somewhat diagrammatic in its character, to show more clearly the distribution and control of the motive fluid.

Figure 6 is a vertical sectional view of a modified form of construction.

In the embodiment disclosed a base is employed, consisting of a lower section 8 having a chamber 9 that constitutes a reservoir for motive fluid. It is supplied from any suitable source by a pipe 10 connected to a nipple 11 formed on one side of the section 8.

25 A vent cock 12 may be provided on one side of the section, and a clean-out opening 13 formed in the bottom of said section is normally closed by a cap plate 14. In the upper portion of the section 8 is formed a vertical piston chamber 15 having a bottom wall 16 that constitutes a partition between said piston chamber 15 and the motive fluid reservoir 9. This bottom 16 has a centrally disposed vertical cylinder 17 that depends into the reservoir 9 and is of considerably less 30 cross sectional area than the same and than the chamber 15. The top of the piston chamber 15 opens through the top of the section 8.

35 Surmounting the section 8 is another section 18 having a bottom wall 19 that constitutes a head for the piston chamber 15. This section 18 is also provided above said head 19 with a vertical piston chamber 20 and the bottom 19 has a centrally disposed upstanding tubular guideway 21 extending 40 into said piston chamber 20.

A head plate 22 is located on the section 18 and constitutes a closure for the upper end of the piston chamber 20. This head plate and the sections 8 and 18 are secured together by side bolts 23 passing through vertical ribs 24 in said sections and engaged with the margins of the head plate 22.

45 Formed on the head plate 22 is an upstanding block 25 which constitutes a mounting, support or holder for metal working or holding dies 26. It will be understood that these may be of various characters and for the purpose of this invention need not be detailed. Over said mounting or block 25, which is thus fixed, is another block 27 that is movable toward and from the block 25 and carries co-operating dies 28.

50 In the piston chambers 15 and 20 are reciprocating pistons 29 and 30. Through diametrically opposite portions of said pistons 29 are formed vertical openings 31. The upper face of the lower piston 29 is provided with sockets 32 surrounding the openings 31. The upper piston 30 is provided with corresponding sockets 33 in its upper and lower 55 sides. The upper movable head block 27 has openings 34 aligned with the openings 30 and 31, and is provided with sockets 35 in its lower sides.

Vertical piston rods in the form of bolts 36 60 pass through the openings 31 and 34, the heads 37 being preferably located against the under side of the lower piston 29 and nuts 38 being located on the upper ends and bearing against the upper head block 27. A pair of spacing sleeves 39 are located on the piston rods or bolts 36 and are interposed between the pistons 29 and 30. The ends of these sleeves fit in the sockets 32 and 33 and said sleeves and piston rods pass through bearing 65 openings 40 formed in the head 19. The sleeves may be provided with suitable packing rings 41. The pistons are thus held in fixed spaced relation. Interposed between the upper piston 30 and the movable head block 27 are corresponding spacing sleeves 42 whose ends are fitted into the sockets 35 of the piston 30 and the sockets 35 of the head block 27.

70 With this structure, it will be evident that the pistons are connected in fixed relation and

that both are in turn fixedly connected to the head block 27. Moreover this connection is such that no canting or cocking of the parts can take place.

5 In the lower vertical cylinder 17 is a piston 43 having a flange 44 on its upper end that bears against the bottom of the piston 29. Said piston is provided in its lower side with a central socket 45.

10 Located upon one side of the base section 18 is a valve casing 47 provided with a cylindrical open ended valve chamber 48. A supply passageway 49 leads from the reservoir chamber 9 in the base section 8 upwardly 15 through said base section and the surmounting section 18 and opens into an annular groove 50 formed in the chamber 48. At one side of said groove 50 is another groove 51, also formed in the chamber 48, and beyond 20 the groove 50 is a second groove 52. From the groove 51 a passageway 53 leads to the upper end of the piston chamber 20. From the grooves 52 a passageway 54 leads to the upper end of the piston chamber 15. From 25 the groove 52 a passageway 55 leads to the dollying hammer 56 which cooperates in a well-known manner with the clamping dies and hammers upon a tool held thereby. The passageway 55 is controlled by a valve 56' in 30 said passageway and seating on a valve seat 57. The valve is urged to its seating position by a spring 58 and has a stem 59 projecting from one end of the valve casing 47.

35 In the valve chamber 48 is a reciprocating plunger valve, comprising terminal heads 60 and 61 connected by a reduced portion 62. This valve has at one end a link connection 63 with an operating lever 64 fulcrumed at 65 on an extension 66 of the valve casing 47.

40 When the valve is in a position, so that the head 60 is interposed between the grooves 50 and 51, motive fluid supplied to the chamber 9, will be cut off from the passageways 53 and 54 and 55. Motive fluid in the chamber 9, 45 however, is sufficient to operate on the piston 43 and elevate the same so as to raise both pistons 29 and 30 as well as die head 27. The die members are thus open so that a tool 50 may be introduced between them. If now the valve actuating lever 64 is moved inwardly, the head 60 will be correspondingly moved and the passageway 53 first brought into communication with the passageway 49. As a 55 consequence motive fluid will flow into the upper piston chamber 20 above the piston 30 and move both pistons and movable die member downwardly because the area of the piston 30 is so much greater than the area of the opposing piston 43. By reciprocating the valve to admit air to said passageways 53 and then cut it off and open the passageway to atmosphere through the open end 67 of the valve chamber 48, a swaging action may be obtained. If additional holding power is de-

sired the valve is then moved so as to open the passageway 54 to communication with the passageway 49, as shown in Figure 5, whereupon motive fluid will operate against both pistons 20 and 30 and hold the upper die head with great power. Upon a still further movement of the valve lever 64 it will strike the projecting end of the valve stem 59, thereby opening the valve 56 and allowing the motive fluid to flow to the dollying hammer. 70

75 In the modification shown in Figure 6 it will be noted that the sockets are done away with in the lower and upper pistons designated respectively 29a and 30a and that the sleeves 39a and 42a abut the faces of said pistons. Preferably however, the sleeves have the intermediate portions of their bores enlarged as indicated at 33a while the piston rods 36a have corresponding portions reduced as shown at 34a. The end portions of the sleeves have a snug fit with the piston rods, however, so that said sleeves are thereby effectively maintained in proper relation. 80

85 From the foregoing, it is thought that the construction, operation and many advantages 90 of the herein described invention will be apparent to those skilled in the art without further description and it will be understood that various changes in the size, shape, proportion and minor details of construction may be resorted to without departing from the spirit or sacrificing any of the advantages of the 95 invention.

99 What I claim, is:

100 1. In apparatus of the character set forth, the combination with a base having a plurality of piston chambers in tandem, of a die member on the base, a second and movable die member coacting with the first member, pistons in the piston chambers, spaced piston rods passing through the pistons and connected to the movable die member, said pistons and die member having sockets in their 105 opposing faces around the piston rods, spacing sleeves on the piston rods between the pistons and between the upper piston and the die member, said sleeves having their ends seated in the sockets, and means for supplying and governing the supply of motive fluid to the piston chambers. 110

115 2. In apparatus of the character set forth, the combination with a base section on which the apparatus is supported and having a piston chamber having a bottom head and an open top, of a second section detachably fitted on the top of the base section and having a piston chamber provided with a bottom wall that constitutes a head for the upper open end of the first piston chamber, said second piston chamber having an open upper end, a head section detachably fitted on the upper end of the second section, and constituting an upper head for the open upper end of the second piston chamber, said head constituting a fixed die member, a movable die 120

125 130

member over the fixed die member, pistons in the piston chambers, and spaced piston rods connecting the pistons together and connecting the pistons to the movable die member.

- 5 3. In apparatus of the character set forth, the combination with a base section on which the apparatus is supported, said base member having a fluid reservoir chamber in its lower portion, a piston chamber above the reservoir chamber and having a bottom wall separating the two, and a smaller open ended piston chamber depending in the reservoir chamber, of a second section detachably fitted on the top of the base section and having
- 10 a piston chamber provided with a bottom wall that constitutes a head for the upper open end of the first piston chamber, said second piston chamber having an open upper end, a head section detachably fitted on the
- 15 upper end of the second section and constituting an upper head for the open upper end of the second piston chamber, said head constituting a fixed die member, a movable die member over the fixed die member, pistons
- 20 in the piston chambers, spaced piston rods connecting the pistons together and connecting the pistons to the movable die member, and a piston in the small depending piston chamber, the last named piston being operated on by the fluid in the reservoir and
- 25 operating against the lowermost piston.

In testimony whereof, I affix my signature.
LORENZO E. CROFT.
